(57)

CLAIM

I claim the ornamental design for a secondary containment structure for vehicles with handles, as shown and described.

DESCRIPTION

FIG. 1 is a top plan view of the secondary containment structure for vehicles with handles;

FIG. 2 is a bottom plan view thereof;

FIG. 3 is a rear elevation view thereof;

FIG. 4 is a front elevation view thereof;

FIG. 5 is a right side elevation view thereof;

FIG. 6 is a left side elevation view thereof; and,

FIG. 7 is a perspective view thereof.

The secondary containment structure for vehicles with handles is shown with a symbolic break to indicate that the claimed design has no specific length and width. The portion of the article between the break lines forms no part of the claimed design.

1 Claim, 7 Drawing Sheets
